UNITED STATES PATENT OFFICE

141,700

DESIGN FOR A NURSERY BOTTLE HOLDER

Betty Dworkin Raport, New York, N. Y.

Application March 30, 1945, Serial No. 118,787

Term of patent 7 years

(Cl. D83—8)

To all whom it may concern:

Be it known that I, Betty Dworkin Raport, a citizen of the United States, resident of the city of New York, in the county of New York, State of New York, have invented a new, original, and ornamental Design for a Nursery Bottle Holder, of which the following is a specification, reference being had to the accompanying drawing, forming part thereof.

In the drawing,

I claim:
The ornamental design for a nursery bottle holder, substantially as shown.

BETTY DWORKEIN RAPORT.
